ANODE CONSTRUCTION

Joseph Slepian, Pittsburgh, Pa., assignor to Westinghouse Electric & Manufacturing Company, East Pittsburgh, Pa., a corporation of Pennsylvania

Application June 3, 1933, Serial No. 674,249

3 Claims. (Cl. 250—27.5)

My invention relates to an anode structure for a vapor electric device and particularly to a protective shield for preventing arc-back.

In the operation of vapor electric devices, the chief difficulty has been the tendency to arc-back or backfire on the inverse half cycle. In order to prevent such backfires, it has been customary to provide deionizing grids in the arc path and to provide shields adjacent to the anode heads.

These grids and shields present surfaces upon which the positive ions and electrons discharge and become neutralized so that a rapid deionization of the space adjacent to the anode head takes place immediately after the end of a conducting period.

However, when metallic grids are used, an inverse arc may establish to the grid itself and from there strike to the anode head.

It is an object of my invention to provide an anode construction in which the danger of arc-back will be minimized.

The anode according to my invention comprises a suitable enlarged anode head of conducting material suspended from the anode stem. A suitable insulating bushing is provided on the anode stem from which is suspended a shield usually of metal which substantially surrounds the anode head. The open end of the shield is provided with a grid of quartz or other suitable non-conducting material. The insulating grid will serve to discharge ions and electrons in substantially the same manner as a metallic grid but because of the insulating nature of the material, substantial currents cannot flow into the grid at one point and out at another so that an arc to the insulating grid cannot form.

Other objects and advantages of my invention will be apparent from the following detailed description taken in conjunction with the accompanying drawing in which the single figure is a sectional elevation of an anode embodying my invention.

The anode construction according to my invention comprises a suitable anode head 1 composed of conducting material such as graphite secured to an anode stem 2 preferably of ferrous material. Surrounding the anode stem is a compound insulating bushing 3 such as disclosed in copending application Serial No. 588,915, filed January 26, 1932.

Suspended from the outer portion of the insulating bushing is a substantially tubular shield 5 preferably of sheet metal. A suitable cap 6 attached to the bushing and the tubular shield 5 substantially closes the space between the tubu-

lar shield and the insulating bushing. The open end of the shield 5 is closed with a suitable grid 10 preferably composed of concentric rings of insulating material such as quartz or aluminum oxide known in the trade as alundum. The insulating grid is held in place by suitable mechanical fasteners such as the cross bolts 11 which are provided with suitable insulators 12.

Since the space between the grid and the anode, and spaces in the grid itself must be deionized by diffusion of the ions to the grid walls, it is clear that this deionization will be most rapid if these spaces are made of small dimensions. Hence the grid is placed in close proximity to the working surface of the anode head 1.

In operation, the insulating grid causes the space between it and the anode to be almost completely deionized, while the space between the grid and cathode remains conducting due to ions coming from the arc to other anodes. The inverse voltage on the anode is thus impressed almost entirely upon this deionized space between the anode and grid, but because of the breakdown characteristics of short spaces in vacuum, this space is well able to withstand this voltage. If for any reason a backfire cause should exist on the insulating grid 10 the non-conducting character of the material will prevent the formation of an arc to the grid and thus nothing will occur to reionize the space between grid and anode. In this manner the insulating grid prevents the formation of inverse arcs or backfires in the vapor electric device.

While I have shown and described a specific embodiment of my invention, it is apparent that changes and modifications can be made therein without departing from the spirit and scope of my invention. I desire, therefore, that only such limitations be imposed as are embodied in the accompanying claims or may be necessitated by the prior art.

I claim as my invention:

1. An anode construction for a vapor-electric device comprising an anode stem, an enlarged anode head on said stem, an insulating bushing 45 surrounding said stem, a metallic shield supported by said insulating bushing and substantially surrounding the lateral surfaces of said anode head, a grid shaped deionizing member of insulating material supported by said shield in 50 closely spaced deionizing position with respect to the lower or active surface of said anode head.

2. An anode construction for a vapor-electric device comprising an anode stem, an enlarged anode head on said stem, an insulating bushing 55

surrounding said stem, a metallic shield supported by said insulating bushing and substantially surrounding the lateral surfaces of said anode head, a grid shaped deionizing member of quartz supported by said shield in closely spaced deionizing position with respect to the lower or active surface of said anode head.

3. An anode construction for a vapor-electric device comprising an anode stem, an enlarged

anode head on said stem, an insulating bushing surrounding said stem, a metallic shield substantially surrounding the lateral surfaces of said anode head, a perforated deionizing member of insulating material supported by said shield in closely spaced deionizing position with respect to the lower or active surface of said anode head.

JOSEPH SLEPIAN.
